(57) **CLAIM**

The ornamental design for a sling mounting apparatus, as shown and described.

DESCRIPTION

FIG. 1 is a perspective view of a sling mounting apparatus showing my new design;

FIG. 2 is a top view thereof;

FIG. 3 is a left view thereof, the right view being a mirror image thereto;

FIG. 4 is a bottom view thereof;

FIG. 5 is a front view thereof;

FIG. 6 is a rear view thereof; and,

FIG. 7 is a perspective view of the sling mounting apparatus of FIG. 1 with a portion thereof pivoted into a second position.

The broken line showings of the sling mounting apparatus are for illustrative purposes only and form no part of the claimed design.
